UNITED STATES PATENT OFFICE.

CHARLES H. GOODYEAR, OF CEDAR RAPIDS, IOWA.

FOLDABLE PASTEBOARD RECEPTACLE.

1,054,530.

Specification of Letters Patent. Patented Feb. 25, 1913.

Application filed May 16, 1912. Serial No. 697,693.

To all whom it may concern:

Be it known that I, CHARLES H. GOOD-
YEAR, a citizen of the United States, and
residing at Cedar Rapids, in the county of
5 Linn and State of Iowa, have invented cer-
tain new and useful Improvements in Fold-
able Pasteboard Receptacles, of which the
following is a specification.

This invention relates to improvements in
10 foldable paste-board receptacles.

An object of the invention is the provision
of a single piece paste-board blank so scored
as to be capable of folding to form both a
receptacle body and a suitable cover there-
15 for.

A still further object is to provide a re-
ceptacle so formed which may be readily
folded into compact flattened form by
merely an opening of the cover and a re-
20 moval of the receptacle contents.

A still further object is the provision of
a receptacle capable of assuming a knocked
down position in a manner similar to a col-
lapsible pocket book and having a foldable
25 side and cover upon a single continuous line
and capable of folding only when said side
and cover are positioned in the same plane
but locked against folding upon said scoring
when in any different planes.

20 With these general objects in view and
others that will appear as the nature of the
invention is better understood, the same con-
sists in the novel combination and arrange-
ment of parts hereinafter fully described,
35 illustrated in the accompanying drawings
and pointed out in the appended claim.

In the drawings forming a part of this
application and in which like designating
40 numerals correspond to similar parts
throughout the several views: Figure 1 is a
plan view of the receptacle body and cover
blank in its unfolded disassembled positions.
Fig. 2 is a perspective view of the assembled
45 box showing the cover thereof opened. Fig.
3 is a perspective view illustrating the box
and cover partially collapsed. Fig. 4 is a
plan view of the assembled box and cover
as folded for shipment, and, Fig. 5 is a
50 transverse central sectional view of the
closed box as secured in that position.

Referring more in detail to the drawings,
the blank 10 is provided with the receptacle
body-portion 11 and closure lid 12, all
55 formed in a single sheet of card-board. The
folding of the side walls 13 and 14 as well
as the end walls 15 and 16 upwardly upon

the rectangular bottom 17 will be apparent
from the scorings upon the blank as well as
their positions assumed in Fig. 2. For the
purpose of assembling the box, said side and
end walls are bent upon the scorings 18 and
60 19 to assume a plane at right angles with
respect to the bottom 17. In that position,
the alternately-arranged similar end flaps
20 are adhesively secured to the inner face
65 of the adjacent wall.

The cover member is formed from the
blank 12 by folding at relatively right
angles thereto the marginal edges 21 thereof
and when so folded may be adhesively se-
70 cured at the overlapping corners or retained
by convenient hold-fast devices such as the
staples 22 herein shown.

The form of the box as shown in Fig. 2
provides the cover adapted for closing over
75 the receptacle body with its edge flap in-
closing the top portion thereof. The box
and cover being so formed provides a per-
manent structure and the further material
elements of the invention consist in a pro-
80 vision whereby the same may be then readily
folded into compact form and then readily
unfolded.

Each of the side walls of the receptacle
is suitably scored as at 23 a point substan-
85 tially centrally of its free edge and running
to alternating corners of the receptacle bot-
tom 11. For the purpose of retaining the
walls in an upright position, a front flap
24 is placed upon the front wall 15 of the re-
90 ceptacle which is adapted to be folded in-
wardly as shown in Fig. 2. It is evident
that upon an unfolding of said locking flap
24 to the position shown in Fig. 3, that each
95 of the box walls may be folded upon the
scoring 23 which will allow each wall to
fold inwardly upon the bottom 11, thus
positioning themselves flatly thereupon as
shown in Fig. 4. As further shown in this
100 latter figure, the scoring 23 upon the rear
wall of the receptacle is continued at 25 in
the same direction entirely across the cover
12 and its marginal flap 21, thus allowing
the cover to fold rearwardly and to one side.
It is noted that in its closed position, the
105 cover lies superposed with respect to a por-
tion of both the rear wall and the adjacent
side wall 13. In the closed position also,
the marginal flaps 21 of the cover are folded
inwardly as indicated.

110 The operation of forming the box from its
knocked down position as shown in Fig. 4

will be at once evident and it will be seen that all that is necessary is to lift the side walls and insert the front locking flap 24 and that then the contents may be placed 5 in the receptacle and the lid or cover placed down over the same. Securing tapes or strings 26 may also be employed provided through perforations in the bottom and side walls of the receptacle and the ends 10 thereof adapted to be tied together as shown in Fig. 5 for securing the cover in its closed position.

While the forms of the invention herein shown and described are what are believed 15 to be preferable embodiments thereof, it is nevertheless to be understood that minor changes may be made in the form, proportion and details of construction without departing from the spirit and scope of the in- 20 vention as set forth in the appended claim.

What I claim as new and desire to secure by Letters Patent of the United States is:—

A device of the class described comprising a bottom, side walls, an end wall, a lid hinged to said end wall, oblique scorings 25 similarly and alternately positioned across each of said walls from one base corner to the center of the top edge thereof, the walls adapted for folding thereupon, the scoring of said end wall being continued in 30 a straight line across said cover and the latter adapted for folding upon said scoring only when positioned in the same plane as said end wall.

In testimony whereof I affix my signature 35 in presence of two witnesses.

CHARLES H. GOODYEAR.
